UNITED STATES PATENT OFFICE.

JOHN STAZIAK, OF SEATTLE, WASHINGTON.

VENDING-MACHINE.

1,072,051.

Specification of Letters Patent. Patented Sept. 2, 1913.

Application filed April 29, 1912. Serial No. 693,937.

To all whom it may concern:

Be it known that I, JOHN STAZIAK, a citizen of the United States, and a resident of Seattle, in the county of King and State 5 of Washington, have invented certain new and useful Improvements in Vending-Machines, of which the following is a specification.

The principal object of this invention is 10 to provide a machine of the character described in which a quantity of newspapers may be stored and from which but one paper at a time may be removed by first depositing a coin in a chute and a subsequent 15 simple manual movement.

The machine is of simple construction and, therefore, not likely to get out of order.

The invention will be fully described in 20 the following specification and shown in the accompanying drawings, in which—

Figure 1 is a top plan view of my device, upon the line $y-y$ of Fig. 2. Fig. 2 is a rear elevation, upon the line $z-z$ of Fig. 1. Fig. 3 is a side elevation, upon the line $x-x$ 25 of Fig. 2. Fig. 4 is an enlarged fragmentary view of the paper ejecting means.

Referring now more particularly to the drawings, reference character A designates, in a general way, the outer casing which is 30 formed of the top 1, end walls 2, front and rear walls 3 and the bottom 4. The lower edges of the end walls 2 are grooved from front to back as at 5, and within these 35 grooves the edges of the bottom 4 are firmly glued or otherwise fixed. At the left hand side of the outer casing A is the partition 6 which extends from front to rear of the casing and is permanently joined to the front and rear walls 3. The bottom 4 does not 40 extend entirely to the front of the casing A (see Fig. 1), but is cut off so as to leave the space 7, which is normally closed by the plate 8 which slides in the forward portions of the grooves 5. Between one of the 45 end walls 2 and the partition 6 is the drawer 9, having the flanges 10 which slide in the ways 11. The drawer 9 extends to the extreme front of the casing A, as shown, and is provided with the knob or handle 12, and 50 any form of suitable lock (not shown). Between the partition 6 and one of the end

walls 2 is the sub-partition 13 which is spaced apart a short distance from the front wall 3 so as to form a coin chute 14 which communicates with the drawer 9, and through the top 1 is the coin slot 15 which is immediately above the coin chute 14. At the front portion of the casing A, and extending from one of the end walls 2 to the other, is the strip 16 the ends of which are 60 firmly secured to the end walls 2.

17 designates a shaft, the ends of which are revolvably mounted in suitable apertures in the top 1 and strip 16 respectively, the said ends being reduced, as shown in dotted 65 lines in Figs. 2 and 3, and near the lower end of the said shaft is secured the worm 18. To the upper end of the shaft 17 is fixed the miter gear 19 which meshes with the similar gear 20, secured to the horizontal 70 shaft 21 which revolves in a suitable aperture through the front wall 3, the extension or collar 22, secured to the wall 3, being provided to afford a wider bearing for the said shaft. At the outer end of the shaft 75 21 is the crank arm 23, and fixed to the opposite end of the said shaft is the arm 24 which normally contacts with the stop bar 25 which slides in the bearing 26 secured to the front wall 3, and which is pivotally connected, at 27, to the lever 28, pivoted at 29 to the front wall 3. Pivoted, at 30, to the opposite side of the wall 3, is the lever 31, to the upper end of which is pivotally connected one end of the bar 32, which slides 80 in the bearing 33 secured to the front wall 3, and the free end of which has the slanting face 34. The lower ends of the levers 31 and 28 are pivotally joined together by the link 35, to one end of which is secured 85 one end of the spring 36, the other end of the spring being secured to the partition 6. Pivoted, at 37, to the partition 6 is the lever 38, one end of which bears against the lever 31 and the opposite end of which 90 extends into the coin chute 14, the pivot 37 being so positioned with relation to the lever that the latter is out of balance and will always find its position as shown in Fig. 2. Fixed to the upper side of the worm 18 is 100 an internally threaded collar 39 into which fits a screw 40, the lower end of which passes

through the worm 18, which is of slightly spring material, so that by turning the screw 40 the lips 41 may be sprung apart and held at any desired degree of separation. This adjustment is necessary for the reason that the papers often vary in thickness. The plate 8 is cut out at 41^a and with the edges of said cut out portion coöperate one end of the projection 42^a which is fixed to the shaft 17 so that, as the shaft 17 rotates the free end of the said projection causes the plate 8 to slide in and out in the grooves 5. Figs. 1 and 3 show the plate 8 in its extreme outward position, and if the shaft 17 be rotated so as to bring the free end of the said projection into contact with the opposite edge of the opening 41^a to that with which it contacts in Fig. 1, a further movement of the said projection will force the plate 8 back toward the front edge of the bottom 4, as will be understood.

The operation of the machine is as follows:—The papers 42, folded as they come from the press, are first loaded into the machine as plainly shown in Fig. 3, the edge of the lowermost paper being placed between the lips 41 of the worm 18 (see Fig. 3). Upon dropping a coin through the slot 15 the shorter arm of the lever 38 will be struck by the coin and cause the shorter arm of the said lever to descend about its pivot 37 which allows the coin to pass through the chute 14 and on into the drawer 9. This descent of the shorter arm of the said lever, of course, causes the ascent of the opposite end thereof which allows the spring 36 to draw the link 35 to the left, which, through the levers 28 and 31, simultaneously moves the bars 25 and 32 to the right and left respectively. The said movement of the bar 25 withdraws it from the circular path of the projection 24 and throws the slanting face 34 into the path of said projection. The crank 23 is now turned clockwise, as viewed from the front of the machine, which brings the projection 24 into contact with the slanting face 34 and, the movement of the crank being continued, forces the said slanting face to the left against the tension of the spring 36, which causes the lower ends of the levers 31 and 28 to move to the right about their respective pivots 30 and 29 until the parts again assume their positions as shown in Fig. 2, the lever 38 assuming its Fig. 2 position by gravity as already explained. The turning of the crank 23 is continued until the projection 24 is stopped by its contact with the free end of the bar 25. Through the miter gears 19 and 20 and shaft 17, the turning of the crank 23 has caused the worm 18 to rotate and, at the same time, through the projection 42^a, has forced the plate 8 outwardly into its position as shown in the drawings, the parts being in those positions at a half

turn of the crank 23. The rotation of the worm 18 has caused the lowermost lip 41 to move out from beneath the edge of the paper which it at first supported, and has allowed the same to drop into its dotted position as shown in Fig. 3, and from which position it can be readily drawn forward and out of the machine. Upon a further half turn of the crank 23 the plate 8 is forced backwardly against the front edge of the bottom 4, as previously explained, and the edge of the next paper automatically enters between the lips 41, and can be removed from the machine by again dropping a coin into the chute 14 and turning the crank a half revolution, as before.

I have shown one form of embodiment of my invention and am aware that obvious changes may be made therein without departing from the spirit and scope of the invention, and I do not desire to be limited to the exact form shown and described.

What I claim as new and desire to protect by Letters Patent is—

1. A paper vending machine comprising, in combination, a paper receptacle having a divided bottom, one portion of which is fixed and the other portion slidable with relation to said receptacle, a worm adapted to alternately support the edges of all the papers and allow the edge of one paper to drop below said bottom when said slidable portion is operated, means for operating said worm and means operable by said first mentioned means for operating said sliding portion, and means for locking said first named means.

2. A paper vending machine comprising, in combination, a paper receptacle having a divided bottom, one portion of which is fixed and the other portion movable with relation to said receptacle, a vertical shaft and a worm thereon adapted to alternately support the edges of all the papers and allow the edge of one paper to drop below said bottom when said slidable portion is operated, a projection on said vertical shaft co-operating with a cam face upon said slidable portion whereby the latter is operated, and a horizontal crank shaft geared to said vertical shaft.

3. A paper vending machine comprising, in combination, a paper receptacle having a divided bottom adapted to be opened and closed, means for automatically opening and closing the said bottom, a worm operable by a portion of said means, said worm adapted to alternately support the edges of all the papers and allow the edge of one paper to drop through said bottom when the same is opened.

4. A paper vending machine comprising, in combination, a paper receptacle having a divided bottom, a portion of which is movable with relation to the other portion, means

for automatically operating said movable portion, a worm adapted to embrace varying thicknesses of papers and operable by a portion of said means, said worm adapted to alternately support the edges of all the papers and allow the edge of one paper to drop down between the portions of said

bottom when said movable portion is operated.

JOHN STAZIAK.
